UNITED STATES PATENT OFFICE.

ERNEST BECKER AND PER O. GISSBERG, OF PERRY, IOWA.

INDOOR-CROQUET GAME.

1,206,194.

Specification of Letters Patent. Patented Nov. 28, 1916.

Application filed December 27, 1915. Serial No. 68,905.

To all whom it may concern:

Be it known that we, ERNEST BECKER and PER O. GISSBERG, a citizen of the United States and a subject of the King of Sweden, respectively, and residents of Perry, in the county of Dallas and State of Iowa, have invented a certain new and useful Indoor-Croquet Game, of which the following is a specification.

10 The object of our invention is to provide an indoor croquet game of simple, durable and inexpensive construction.

15 A further object is to provide a set of arches built to play croquet indoors on a floor or on tables with cues.

20 Still a further object is to provide such a device in which all of the arches are operatively connected with each other by adjustable mechanism, whereby the positions of the arches may be varied to suit the conditions of a floor or table or the like.

25 Still a further object is to provide such a device with suitable means for locking the device to a table when necessary or desirable.

Our invention consists in the construction, arrangement and combination of the various parts of the device, whereby the objects contemplated are attained as hereinafter more 30 fully set forth, pointed out in our claims and illustrated in the accompanying drawings, in which:

Figure 1 shows a top or plan view of a top of a billiard table, equipped with a 35 croquet attachment embodying our invention. Fig. 2 shows a side elevation of the same. Fig. 3 shows an end elevation of the croquet game device. Fig. 4 shows an enlarged, detail, sectional view, taken on the line 4—4 of Fig. 1. Fig. 5 shows a vertical, 40 sectional view, taken on the line 5—5 of Fig. 1. Fig. 6 shows a detail view in side elevation of one of the clamping devices, and Fig. 7 shows a detail view of one of the 45 members of the device, showing the roughened face thereon.

In the accompanying drawings, we have used the reference numeral 10 to indicate generally a billiard table, which may be of 50 ordinary construction, and is used in connection with our croquet game device for playing a variety of games, somewhat similar to the ordinary croquet game.

It will be understood that where a table 55 of the type shown herein is used, cues are

used for driving the croquet balls. The table has the ordinary rail 11 and cushion 12.

Our improved croquet game device comprises an upright member 13 having on its upper end a suitable handle or ball 14. 60

Mounted on and supporting the lower end of the upright member 13 are opposite arch members, each comprising upright portions 15 engaging the opposite sides of the member 13 and secured thereto by means of a 65 bolt 16 extending through said members 15, and held in place by a thumb nut 17. Extending downwardly and outwardly from the members 15 are arch members 18, at the outer ends of which are downwardly extending lugs or members 19. On the lower ends of the members 14 are suitable cushioning feet 20. 70

Arranged quarterwise around the member 13 from each of the members 18, are 75 similar arch members, the similar parts being indicated by the reference characters already used, with the addition of the letter "a". That is to say the upright opposite members which are secured to the member 80 13 are indicated by the reference characters 15^a. The outwardly and downwardly inclined members are indicated by the reference character 18^a. The downwardly inclined member at the outer ends of the member 18 are indicated by the character 19^a. On the lower ends of the members 19^a are 85 cushion devices 20, similar to those already described. The members 15^a are secured to each other and to the member 13 by means 90 of a bolt 16.

Mounted on the member 13 above the arches at the lower end thereof is a sleeve 21 having four outwardly extending flanges arranged in a series quarterwise around the 95 sleeve, as shown in Figs. 2 and 3. The sleeve 21 is adjustably held in position, at any height on the member 13 by means of a setscrew 23. Pivotal secured to the flanges 22 are frame members 24, 25, 26, and 27 extending respectively toward the head, the sides and the foot of the table and preferably inclined somewhat downwardly toward their outer ends, as shown in Fig. 2. 100

The members 24 to 27 inclusive are preferably arranged to receive other frame members 28, 29, 30 and 31 respectively, which are adjustably mounted by means of set-screws 32. 105

At the outer end of each member 28 to 31 110

inclusive is a vertical face as shown in Fig. 4, secured to a member 36 by means of a bolt 37 on which is a wing nut 38. The face and member just mentioned are preferably roughened or corrugated.

Formed on the member 36 is a flat faced member 39 arranged at right angles to the member 36. Secured to the members 39 near the head and foot of the table are frame members 40 and 41, having flattened portions designed to engage the member 39 and to be secured thereto by bolts 37 and thumb nuts 38, similar to those already described. The members 40 and 41 respectively extend downwardly and away from each other and toward the table.

The outer flattened ends of the members 29 and 31 are secured to members 36 as already described, and also to brace members 42 which will be hereinafter referred to. The lower members 39 at the sides of the table are secured to flattened portions 43 formed on the upper ends of opposite downwardly extending frame members 44. At 25 the outer end of each frame member 44 is a flattened face designed to engage and be secured to another member 36 similar to that already described, having formed on it a member 39 similar to the member 39 already described.

It will be understood that the flattened members on the ends of the members 44 are secured to the members 36 by means of bolts 37, such as have been described.

Secured to the member 35 at the lower outer end of each member 44 are flattened faces at the upper ends of arch members 45 and 46, which extend downwardly in opposite directions to the table and are provided 10 with cushioned feet 20 such as have been already described. The flattened faces at the upper ends of the members 45 and 46 are secured to the adjacent member 39 by means of the bolt 37 and wing nut 38, such as have been already described.

At the lower end of each member 40 and 41 near each end of the table is a flattened portion secured to the member 36, similar to that already described, in a manner hereinbefore referred to.

The members 36 at the lower ends of each member 40 and 41 have members 38 and 39 formed thereon, and suitably secured to the flattened upper ends of arch members 45 by means of bolts 37. It will be seen that on account of the construction hereinbefore described, the distance of the upper ends of the members 28 and 30 from a post or upright 13, and the distance of the members 29 and 30 from said upright may be varied as desired by adjusting the set-screws 32. Some adjustment can also be made by vertically varying the position of the member 31 from the upright member 13. The distance of the two arches near the head of the

table from each other may be easily varied by loosening the proper wing nut 38 and lowering the upper ends of the members 40 and 41. The width of any of the arches, except the center arch may be varied in the same way by loosening the proper set-screw. In the same way the distance of the side members from each other may be changed as desired, and the width of said arch may be adjusted.

The brace member 42, hereinbefore referred to, extends laterally and is pivotally secured to a clamping device 50 made of resilient material and adapted to be extended over the cushion and side rail of the table, and to be locked in position by means of a screw 51 extended through the upright portion 52 of the bracket 50 by a screw-threaded connection, and having swiveled on its inner end a pad 53. Similar braces 50 are secured at the ends of the table and support brackets 54 having vertical bearings 55 to receive the stakes 56.

The advantages of the construction hereinbefore set forth may be largely seen from the foregoing description.

The device is readily and easily taken apart and packed in a small place for storage and transportation. It may be easily assembled and mounted on a table or the like and can be quickly and easily adjusted for placing the arches in a great variety of positions with relation to each other, and also for varying the width of the arches. By loosening the clamps at the side of the table, the whole device may be removed from the table by grasping the handle 14 and lifting it upwardly.

Some changes may be made in the construction and arrangement of the parts of our improved device without departing from its essential features and purposes, and it is our intention to cover by this application any such changes which may be included within the scope of our claims.

We claim as our invention:

1. A croquet game device comprising an upright member, arch supporting members secured to the lower ends thereof, frame members pivotally secured to said upright members and extending downwardly and away therefrom in different directions, frame members adjustably mounted on said first described frame members respectively and arches adjustably mounted on said last described frame members.

2. A croquet game device comprising an upright member, arch supporting members secured to the lower ends thereof, frame members pivotally secured to said upright members and extending downwardly and away therefrom in different directions, frame members adjustably mounted on said first described frame members respectively and arches adjustably mounted on said last

described frame members, said arches being adjustable in width.

3. A croquet game device comprising an upright member, arch supporting members secured to the lower ends thereof, frame members pivotally secured to said upright members and extending downwardly and away therefrom in different directions, frame members adjustably mounted on said 10 first described frame members respectively, and arches adjustably mounted on said last

described frame members, and means for locking said device on a table.

4. In a device of the class described, the combination of a table with a supporting 15 member, a plurality of arches adjustably mounted thereon and adapted to be supported in different positions on said table.

Des Moines, Iowa, November 27, 1915.

ERNEST BECKER.
PER O. GISSBERG.
